ATTORNEYS.

UNITED STATES PATENT OFFICE.

CLARA V. HAVENS, OF NEW YORK, N. Y.

BRASSIÈRE.

1,387,224.

Specification of Letters Patent. Patented Apr. 20, 1920.

Application filed October 15, 1918. Serial No. 330,710.

To all whom it may concern:

Be it known that I, CLARA V. HAVENS, a citizen of the United States, residing in the city, county, and State of New York, have 5 invented a new and useful Brassière, of which the following is a specification.

My invention consists of a brassière which is composed of the body of the brassière the same being composed of a band adapted 10 to be adjusted in its fitting relative to the bust measure and the corset over which latter it is worn, and retain its position and yield so as to conform to the motions of the body of the wearer, while being inexpensive 15 and practical, presenting an attractive appearance and nicely covering the corset, as will be hereinafter fully described.

The invention is satisfactorily illustrated in the accompanying drawing, but the important instrumentalities thereof may be varied, and so it is to be understood that the invention is not limited to the specific details shown and described, as long as they are within the spirit or scope of the claims. 25 Figure 1 represents a front perspective view of a brassière in operative condition embodying my invention.

Fig. 2 represents a rear perspective view thereof.

Fig. 3 represents a front perspective view thereof in open condition.

Fig. 4 represents a top edge plan view of a portion of the front of the device.

Similar numerals of reference indicate 35 corresponding parts in the figures.

Referring to the drawings:

1 designates a band of suitable fabric adapted to be passed around and over a corset for the purpose usual in such cases, 40 it being composed of the front pieces 2, the back piece 3, the latter being extended forward to comprise the sides 4 of the band, said sides joining the rear terminals of the front pieces 2—2 as at 5 where the joints 45 are strengthened by the stays 6.

The front pieces 2 normally separated are of such length that they are adapted to cross each other slidingly, and so close the front of the band, said pieces being furthermore extended downward and tapering to the lower ends forming the tabs 7 with whose lower ends are connected the body bands or belts 8 which are adapted to be passed around the relative portions of the 55 corset and brought together in front thereof of the same and the brassière where they

are tied or secured and so prevented from improper opening.

Depending from the underside of the front pieces 2 intermediate of the terminals 60 thereof are the loops 9 which are somewhat V shape when in normal condition and formed of elastic strap-like members so that when the body is placed on and around the corset said loops may be brought together 65 and their bottom bends may meet and register and be fitted on a hook, button or other attachment on a portion of the lower portion of the front of the corset, thus retaining the body and especially the front pieces 70 2 thereof taut and snug on the corset, the loops 9 owing to their resiliency permitting the body to adjust itself to different sizes of wearers, and allowing the front pieces to yield to and conform with the motions of the portions of the body of the 75 wearer within the corset.

The upper ends of the pieces 2 are provided with hooks 10 and eyes 11 respectively for closing the top of the band, and shoulder straps 12 are attached to pieces 2 and 3 for sustaining the brassière from above. 80

It will be seen that when the band is opened, as in Fig. 3, it may be adjusted on and around the corset, the straps 12 being 85 placed over the shoulders of the wearer. The hooks and eyes are connected and the loops 9 fitted to the attachment on the corset.

The bands 8 are then run around the corset properly tightened, and their end portions united by a bow knot or other fastening thereof when the brassière is in place and it will provide a proper covering for the corset, may be worn with comfort and it will present an attractive appearance, and the loops will yield to the motions of the corset and the relative portion of the body of the wearer and resiliently adjust themselves to said motions, while the band will remain in proper position with the crossed 90 front pieces 2—2 held taut on each other 95 and on the corset without wrinkling, puckering, or the like.

The hooks and eyes 10 and 11 may be placed and secured according to the bust 105 measure so that the upper portion of the brassière may be widened or narrowed so as to be adjusted relatively to said measure and set properly over the corset and held closed and taut when so adjusted while the 110 lower portion of the garment is held closed and taut in front by the attaching loops 9

and around the body of the wearer by the bands 8.

The brassière when adjusted over the corset will be sufficiently high to cover the portion of the diaphragm or flesh of the wearer just above the top line of the corset, thus concealing said top line, while the resilient loops 9 in expanded condition and the belts 8 run around the corset draw on the brassière to keep the latter reduced in width on the corset.

Having thus described my invention what I claim as new and desire to secure by Letters Patent, is:—

- 15 1. A brassière for a corset formed of a body composed of front and rear members, and tabs extending downwardly from the front members, said tabs being adapted slid-
ingly to cross each other and provided with
- 20 means of attachment to a proper part of a corset to which the brassière is applicable.

2. A brassière formed of a body, the front

members of which extend laterally in opposite directions and are adapted to cross each other, and loop-like pieces of elastic material secured to the opposite front members and depending therefrom and attachable to a corset and adapted to form a downward draft on said members in opposite directions and retain them in position on the corset. 25

3. A brassière for a corset composed of front and rear members of fabric, and tabs extending downwardly from the front members, said tabs being adapted to cross each other slidingly, resilient loop-like members 30 depending from said tabs and adapted to be attached to an adjacent portion of a corset, said tabs tapering downwardly, and a body band connected with the lower portions of said tabs.

CLARA V. HAVENS.
